UNITED STATES PATENT OFFICE.

WILLARD F. RICHARDS, OF BUFFALO, NEW YORK, ASSIGNOR TO GOULD COUPLER COMPANY, A CORPORATION OF NEW YORK.

DYNAMO SUSPENSION.

1,359,920.

Specification of Letters Patent. Patented Nov. 23, 1920.

Application filed July 30, 1915. Serial No. 42,696.

To all whom it may concern:

Be it known that I, WILLARD F. RICHARDS, a citizen of the United States, and a resident of Buffalo, county of Erie, State of New York, have invented certain new and useful Improvements in Dynamo Suspensions, of which the following is a specification.

My invention relates to improvements in suspensions for dynamos driven from a car axle, such dynamos being commonly used for lighting railway cars. The main object of my invention is to provide a simple and efficient arrangement for supporting the dynamo, which will be easily accessible for inspection and repairs. Further objects, features and advantages will more clearly appear from the detailed description given below, taken in connection with the accompanying drawings which form a part of this specification.

In the drawings Figure 1 is a side view of part of a car with my invention in one form applied thereto, certain parts being broken away and shown in section to more clearly illustrate the arrangement. Fig. 1^a is a detail illustrating the method of securing the carrying frame to the supporting frame. Fig. 2 is a section taken on the line 2—2 of Fig. 1. Fig. 3 is a similar view looking at the dynamo in the opposite direction. Fig. 4 is a detail view of the dynamo suspension shown in Fig. 1, illustrating the parts in a different position. Figs. 5, 6 and 7 are views similar to Fig. 4, but illustrating modifications.

Referring to Figs. 1 to 4, 1 represents a car body having a center beam 2. One of the car axles is shown at 3, provided with a pulley 4, over which passes a belt 5 driving the dynamo 6. A frame for supporting the dynamo comprises a member 8, secured to the underneath side of the car body by being connected to cross beams by bolts 9 and stirrup member 10, secured to the member 8 by means of bolts 11, and also a cross member 12, one end of which is bolted to the stirrup 10, by bolts 13, and the other end of which is bolted to the center beam 2 by means of bolts 14. Adjustably secured on the member 12 is a carrying frame 15, having depending lugs carrying a pivot rod 16, from which the dynamo 6 is pivotally suspended by means of lugs 17 rigid with the dynamo. The carrying frame 15 is secured to the

cross member 12 by means of bolts 18 passing through slots 60 in the member 12 and slots 61 in the carrying frame 15 (see Fig. 1^a), so that the frame 15 is adjustable in all directions laterally over the face of the member 12 and may be secured in any of its adjusted positions by tightening the bolts 18. The frame 15 is firmly held in adjusted position by means of set screws 19. Carried by the frame 15 is a bell crank lever 20, the lower end of which is connected with the dynamo by a link 21. Connected to the short arm of the bell crank lever 20 is a rod 22, passing through an opening in the depending arm 23, integral with the frame 15. A coil spring 24 surrounds the rod 22 and is compressed by means of a hand nut 25, screw threaded on the rod 22 against an abutment disk 26 loose on the rod 22 and bearing against the arm 23. It will be clear from Fig. 1 that the compressed spring 24 acts as a tension device, tending to swing the bell crank lever 20 to the right, thereby tending to move the dynamo away from the car axle and maintain tension on the belt. The tension which the spring exerts may be adjusted by turning the hand nut 25. If it is desired to relieve the tension on the belt or make the belt slack, in order to remove it or in order that the dynamo may be motored for testing, the dynamo 6 is moved toward the axle in a direction to compress the spring 24, and when the pivot 27, by which the rod 22 is connected to the short arm of the bell crank 20, passes the dead center, the spring will then tend to force the dynamo toward the car axle. At the same time the long arm of the bell crank 20 and link 21 will pass the dead center, as shown in Fig. 4, so that the dynamo will be locked in the position shown in Fig. 4, independently of the spring 24. That is, in the position shown in Fig. 4, even if the spring 24 were absent, the dynamo would still retain the position there shown, because the weight of the dynamo, tending to swing it downwardly, tends to force the link 21 upwardly against lever 20 and thus maintain the bell crank lever 20 in the position shown with its short arm 28 bearing firmly against the frame 15. The bell crank lever 20 and link 21 thus form a toggle lever arrangement for moving the dynamo about its pivot toward and from the axle, the tension device normally tending to cause the toggle

arrangement to swing the dynamo away from the car axle to maintain tension on the belt 5, but acting to force the dynamo toward the car axle upon the dynamo being moved a certain distance toward the car axle and positively lock the dynamo in such position with the belt slack and with the toggle lever holding the dynamo in such position independently of the tension device.

In the arrangement shown in Fig. 5, the bell crank lever 30 is pivoted to the carrying frame 15, but the arms of the bell crank are arranged in a somewhat different position relatively to one another. Thus the rod 31 pivoted to the end of the short arm of the bell crank normally extends above the pivotal center 32 of the bell crank and passes through an opening in a depending arm 33 of the frame 15 and has a spring 34 surrounding its outer end and compressed against the arm 33 by means of a hand nut 35, the bell crank being connected to the dynamo 6 by means of a link 36. The spring 34 being compressed by the nut 35, tends to swing the bell crank 30 so as to pull the dynamo away from the car driving axle and thus maintain the proper tension on the belt.

In the modification shown in Fig. 6, the toggle, comprising links 40 and 41, is used for moving the dynamo toward and from the car axle. One end of the link 40 is pivoted to the frame 15 and one end of the link 41 to the dynamo, the other ends of the two links being pivoted to one another by means of pivot pin 42, to which is also pivoted a rod 43 passing loosely through a member 44, journaled in a depending arm 47 at 48. The coil spring 45 surrounds the outer end of the arm 43 and is pressed against the member 44 by means of a hand nut 46 screw threaded on the outer end of the rod 43. The spring 45 therefore acts as a tension device tending to pull the pivot 42 toward the arm 47 and thus force the link 41 downwardly by reason of the toggle action of the links 40 and 41, and so tend to force the dynamo 6 away from the car axle to maintain proper tension on the belt.

In the arrangement shown in Fig. 7, toggle links 50 and 51, pivotally connected together and also pivotally connected to the frame 15 and dynamo 6 respectively, are acted upon by a rod 52, one end of which is pivoted to the common pivot of the links 50 and 51, and the other end of which passes through a depending arm 53 on the frame 15. A coil spring 54 has one end bearing upon a member 55 which bears upon the member 53. The spring is compressed by means of a hand nut 56, screw threaded on the inner end of the rod 52. The spring 54 therefore acts on the toggle links 50 and 51 to tend to force the link 51 downwardly and

the dynamo away from the car axle to maintain the tension on the belt 5. By means of the hand nuts for adjusting the compression of the tension springs, any desired tension may be placed upon the driving belt 5.

Although I have described my improvements in great detail and with respect to particular embodiments of the invention, I do not desire to be limited to such details except as clearly pointed out in the appended claims, since many changes and modifications may well be made without departing from the spirit and scope of my invention in its broader aspects.

What I claim as new and desire to secure by Letters Patent is:

1. A dynamo suspension for cars, having in combination with the car and its axle a supporting member secured to a car body, a dynamo pivotally suspended therefrom, a belt driving the dynamo from the car axle, a toggle arrangement for moving the dynamo about its pivot toward and from the car axle and a tension device acting on said toggle arrangement and tending to swing the generator away from the driving axle, said toggle arrangement being adapted to operate past its dead center in opposition to said tension device.

2. A dynamo suspension for cars having in combination with the car and its axle, a dynamo pivotally suspended, a belt driving the dynamo from the car axle; a toggle arrangement for moving the dynamo about its pivot toward and from the car axle and a tension device acting on said toggle arrangement and tending to swing the generator away from the driving axle, said toggle arrangement being adapted to operate past its dead center.

3. A dynamo suspension for cars, having in combination with the car and its axle, a dynamo pivotally mounted, a belt driving said dynamo from a car axle, and a tension device normally tending to swing the dynamo away from the car axle but acting to force the dynamo toward the car axle upon the dynamo being moved a certain distance toward the car axle and positively lock the dynamo in such position toward the axle and with the belt slack.

4. A dynamo suspension for cars having in combination with a car and its axle, a dynamo having lugs rigid therewith, a belt driving the dynamo from the car axle, a frame rigid with the car body, said lugs being pivotally connected directly to said frame whereby the dynamo is pivotally suspended from the car body, a pivoted toggle lever for swinging said dynamo about said pivot and a spring acting on said toggle lever and tending to swing the dynamo away from the axle and means for adjusting the tension of said spring.

5. A dynamo suspension for cars having

in combination with the car and its axle, a dynamo pivotally suspended, a belt driving the dynamo from the car axle, a toggle lever arrangement for swinging the dynamo toward and from the car axle, and a tension device acting on the toggle lever arrangement to normally swing the dynamo away from the car axle, but acting to force the dynamo toward the car axle upon the dynamo being moved a certain distance toward the car axle, and positively lock the dynamo in such position with the belt slack and with the toggle lever arrangement holding the dynamo in such position independently of the tension device.

6. A dynamo suspension for cars having in combination with the car and its axle, a dynamo pivotally mounted, a belt driving the dynamo from the car axle, a lever arrangement for swinging the dynamo toward and from the car axle, and a spring acting on the lever arrangement to normally swing the dynamo away from the car axle, but acting to force the dynamo toward the car axle upon the dynamo being moved a certain distance toward the car axle, and positively lock the dynamo in such position with the belt slack and with the lever arrangement holding the dynamo in such position independently of the spring.

7. A dynamo suspension for cars having in combination with the car and its axle, a dynamo pivotally suspended from the car body, a belt driving the dynamo from the car axle, a toggle lever arrangement for swinging the dynamo toward and from the car axle, and a tension device acting on the toggle lever arrangement to normally swing the dynamo away from the car axle, but acting to force the dynamo toward the car axle upon the dynamo being moved a certain distance toward the car axle, and positively lock the dynamo in such position with the belt slack and with the toggle lever arrangement holding the dynamo in such position independently of the tension device, and a nut for adjusting the tension of the tension device.

8. A dynamo suspension for cars having in combination with the car and its axle, a dynamo pivotally mounted from the car body, a belt driving the dynamo from the car axle, a lever arrangement for swinging the dynamo toward and from the car axle, and a spring acting on the lever arrangement to normally swing the dynamo away from the car axle, but acting to force the dynamo toward the car axle upon the dynamo being moved a certain distance toward the car axle, and positively lock the dynamo in such position with the belt slack and with the lever arrangement holding the dynamo in such position independently of the spring and means for adjusting the tension of the spring.

9. A dynamo suspension for cars having in combination with the car and its axle, a supporting frame secured to the underneath side of the car body, a carrying frame adjustably secured on said supporting frame, a pivot rod carried by the supporting frame, a dynamo pivotally suspended on said pivot rod, a belt driving the dynamo from the car axle, a toggle lever arrangement for swinging the dynamo toward and from the car axle, and a tension device acting on the toggle lever arrangement to normally swing the dynamo away from the car axle, but acting to force the dynamo toward the car axle upon the dynamo being moved a certain distance toward the car axle, and positively lock the dynamo in such position with the belt slack and with the toggle lever arrangement holding the dynamo in such position independently of the tension device.

10. A suspension for dynamos driven from car axles having in combination with the car and its axle, a supporting frame secured to the underneath side of the car body, a carrying frame secured to the supporting frame and adjustable with respect thereto toward and from the driving car axle, a dynamo having lugs rigid therewith, normally loosely pivoted to said carrying frame around a single axis, and a compressed spring tending normally to swing the dynamo away from the car axle.

11. A suspension for dynamos driven from car axles having in combination with the car and its axle, a supporting frame secured to the underneath side of the car body, a carrying frame secured to the supporting frame and adjustable with respect thereto toward and from the driving car axle, a dynamo having lugs rigid therewith, normally loosely pivoted to said carrying frame around a single axis, a belt driving the dynamo from the driving car axle, a spring tending normally to swing the dynamo away from the car axle, and means for adjusting the tension of said spring.

12. A suspension for dynamos driven from car axles, having in combination with the car and its axle, a center beam on the bottom of the car body, a detachable supporting frame having one end secured to said beam and the other end secured to the car body, a carrying frame adjustably secured to said supporting frame and a dynamo supported to swing from said carrying frame.

13. A dynamo suspension having in combination with a car and its axle, a frame rigidly secured to the car body, a dynamo having lugs rigid therewith and pivoted to said frame whereby the dynamo is pivotally suspended from the car body, a belt driving the dynamo from the car axle, a tension device comprising a spring tending to swing the dynamo away from the driving axle, and

means for adjusting the tension of said spring independently of the adjustment of said pivotal support, said tension device normally tending to swing the dynamo away from the car axle, but acting to force the dynamo toward the car axle upon the dynamo being moved a certain distance toward the car axle.

14. A dynamo suspension having in combination with a car and its axle, a frame rigidly secured to the car body, a dynamo having lugs rigid therewith and pivoted to said frame whereby the dynamo is pivotally suspended from the car body, a belt driving the dynamo from the car axle, a tension device comprising a spring under compres-

sion, tending to swing the dynamo away from the driving axle, and means for adjusting the tension of said spring independently of said pivotal support, said tension device normally tending to swing the dynamo away from the car axle, but acting to force the dynamo toward the car axle upon the dynamo being moved a certain distance toward the car axle, and positively lock the dynamo in such position toward the driving axle with the belt slack and independent of the spring.

In testimony whereof I have signed my name to this specification.

WILLARD F. RICHARDS.
